UNITED STATES PATENT OFFICE.

FRANK C. LA MAR AND PETER J. HOPKINS, OF PITTSBURGH, PENNSYLVANIA.

RENEWABLE ELECTRIC FUSE.

1,318,886.

Specification of Letters Patent. Patented Oct. 14, 1919.

Application filed June 20, 1918. Serial No. 240,892.

To all whom it may concern:

Be it known that we, FRANK C. LA MAR and PETER J. HOPKINS, citizens of the United States, residing at Pittsburgh, in the 5 county of Allegheny and State of Pennsylvania, have invented new and useful Improvements in Renewable Electric Fuses, of which the following is a specification.

This invention relates to inclosed or cartridge fuses of the renewable or refillable type, wherein the fusible element or strip is removably mounted in a casing or shell, so that when the fusible element is blown out or disrupted by an excess or overload 10 current, the disrupted or otherwise defective fuse may be removed and replaced by another.

The object of the invention is to provide a fuse of this type of improved, simple 20 and economical construction, and which is easily and readily renewed, and which will effectively withstand the force and effects of the explosion and products of combustion which take place within the shell or casing 25 when the fuse is blown or burnt out.

The invention consists in a fuse comprising a shell or casing of fiber or other suitable substantially refractory and insulating material, having external screwthreads upon 30 its ends, washers fitted in the ends of the shell or casing and adapted to hold and support the fusible element in proper position within the shell or casing, and internally threaded end caps fitted on the ends 35 of the shell or casing and engaging the ends of the fusible element and firmly holding or binding its ends against the washers to secure good contact between the parts, and in the details of construction, combination 40 and arrangement of parts, all substantially as we will proceed now more particularly to set forth and finally claim.

In the accompanying drawings, in the several figures of which like parts are similarly designated, Figure 1 is a side elevation of the fuse assembled and ready for use. Fig. 2 is a longitudinal section, on a larger scale, the fuse element being shown in full lines. Fig. 3 is a horizontal section, taken 50 substantially in the plane of the line 3-3, Fig. 2, and at right angles to the section of said figure, and looking in the direction of the arrows. Fig. 4 is a vertical transverse section, taken substantially in the 55 plane of line 4-4, Fig. 2, and looking in

the direction of the arrow. Fig. 5 is a detail view of one of the end washers. Fig. 6 is an elevation of one end of the casing with the end cap removed, and Fig. 7 is a sectional detail view, on a larger scale, of 60 a portion of the fuse, showing the end cap provided with a pressure screw for effecting additional pressure upon the ends of the fuse element and maintaining contact between the fuse element and washers. 65

As shown in the drawings, the shell or casing comprises the body portion 1, of tubular form, which may be constructed of fiber or any other suitable hard substantially refractory and insulating material, 70 and having its ends reduced at 2, to form shoulders 3. Upon the reduced ends of the shell or casing are fitted metal ferrules 4, and as herein shown, these ferrules are constructed of a section of straight metal tubing preferably brass, of an internal diameter sufficient to fit snugly upon the reduced ends of the body portion 1, with its inner end abutting against the shoulder 3, and of such length that its outer end projects beyond or overhangs the ends of the body portion to afford seats 5 within the ferrules for fuse element anchoring washers to be described. The said ferrules 4 are provided externally on their inner ends with 80 screwthreads 6, which for the purpose of this invention extend only to about the center of the ferrule. In assembling these parts, the ferrules 4 are fitted or forced upon the reduced ends 2 of the tubular body portion 1 until their threaded ends abut against the shoulders 3, and then the metal of the ferrules just beyond the threads is rolled or spun downwardly or inwardly into the fiber of the shell, as shown in Fig. 2, to 85 form an annular or circumferential groove 7 in the exterior of the ferrule, and to effect a locking of the ferrule upon the end of the body portion against longitudinal movement or displacement of the ferrules. Pins 100 8 may be driven through the ferrules and into the fiber of the shell or tube at any suitable place, as shown in Fig. 2, to prevent rotation of the ferrules upon the shell.

During the process of rolling the grooves 105 7 in the ferrule, the outer ends of the ferrules are also slightly reduced to afford a clearance space 9 between the ends of the ferrules and the interior of the end caps to be referred to for the escape of gases of 110

combustion from the interior of the shell to the grooves for a purpose as will be hereinafter explained.

Fitted in the seats 5 in the ends of the shell or casing, are fuse element or strip anchoring washers 10, said washers preferably, and as herein shown, being constructed of circular pieces of metal, such as brass, and having a portion of their periphery slabbed off, as at 11, and of such diameter and thickness to fit snugly in the ends of the ferrules 4, with their inner surface engaging the ends of the fiber shell or casing, and their outer surface substantially flush with the ends of the metal ferrules 4, the slabbed off portions 11 of the washers 10 affording a passage 12 from the interior of the shell for the fuse element or strip 13, which may be of any usual or ordinary construction, and as herein shown comprises a flat strip of fusible metal provided with any suitable number, preferably three, readily fusible restricted or reduced blow-out portions 14 between its ends, which are adapted to be bent over, as at 15, the slabbed off portions of the washers against the outer surface thereof.

In order to close the ends of the shell or casing, and to effect a good and firm contact between the bent over ends of the fuse element and the washers, caps 16 are provided, said caps being provided with internal threads 17 terminating short of the end wall or head of the cap, and adapted to engage the threads on the ferrules 4 to secure the caps in place. The end wall or head of the caps 16 is provided with a central hole or perforation 18 to afford a gas opening or escape passage, which as shown lies over the bent ends of the fuse element.

In order to securely lock the end caps upon the ends of the casing or shell against accidental displacement or becoming loose and disturbing a good electrical contact between the parts, the screwthreads on the ferrules 4 and the end caps 16 are constructed of gradually increasing pitch from the end of the fuse inwardly, as shown more clearly in Figs. 2 and 6, so that when the caps are screwed upon the ends of the fuse and are about to reach their final adjustment, the initial threads of lesser pitch on the ferrules and caps will be caused to bind, due to the advancing action of the threads 55 of greater pitch, thus effectively locking the end caps in place against accidental displacement or becoming loose from shocks or vibrations or other causes.

As shown in Fig. 7, the end caps 16 may be provided with a set screw 19, comprising an annular head 20 and a threaded shank 21, the head 20 fitting in a countersunk recess 22 in the inner wall of the end cap, and the threaded shank 21 engaging a threaded opening through the end cap and exposed

upon the outside, and provided with a nick or otherwise constructed to receive an operating tool. The set screw 19 is arranged adjacent to the gas escape opening 18 in the end wall of the cap, or in any other suitable place, so that it will overlie the bent ends of the fuse element, and after the fuse is assembled, the said set screw may be manipulated or screwed inward against the ends of the fuse element and thus afford additional pressure upon the parts to effect and maintain a good contact therebetween, and furthermore, the set screw 19 also serves by its outward pressure upon the end caps to aid in effecting a binding or locking action between the threads of the ferrules and end caps.

In assembling the fuse, the operator takes the fuse element, which as hereinbefore stated, comprises a thin flat strip of fusible metal, and positions one of its ends over the slabbed off portion of one of the washers and bends the end of the strip down upon the outer face of the washer, and then passes the free end of the strip through the shell or casing and places the washer with the fuse bent thereon into the seat 5 in the end of the shell, the opposite end of the fuse element projecting from the other end of the shell. The operator then places another slabbed off washer in the other end of the shell, with the fuse strip projecting over the slabbed off portion of the washer, care being taken that the slabbed off portion of the last inserted washer is arranged in a position 100 diametrically opposite the slabbed off portion of the washer inserted in the other end of the shell, and the other end of the fuse element bent down upon the outer face of the washer reversely to the bend of the 105 other end thereof, thus securing an oblique or diagonal arrangement of the fuse element in the shell, as is common in this type of fuse, and as shown in Fig. 2 of the drawings. The end caps are then placed upon 110 the shell and screwed to place, the end walls of the caps engaging the bent ends of the fuse element and forcing them against the washers, and with a little pressure the threads of varying pitch will effectively 115 lock the end caps against accidental displacement and becoming loose, and thus maintaining and securing the parts in good electrical contact.

In the modification shown in Fig. 7, the 120 fuse is similar to that above described and in addition the end caps are provided with the set screws 19, and after the fuse is assembled as above described, the said set screws may be engaged by a proper tool and turned to force their heads 20 into contact with the bent ends of the fuse element, to thereby assist in maintaining a perfect contact between the fuse element and the washers, and also exert a back pressure on 130

the end caps and thereby assist in effecting a locking engagement of the threads on the ferrules and end caps.

By this construction, when the fuse is blown or disrupted by an excess or overload current, the fuse element becomes separated, and the confined gases within the shell gradually escape from the interior of the shell, some of the gas finding its way into the annular grooves 7 in the ferrules 4, which affords an expansion chamber therefor, and eventually leaks out through the screwthreads until the pressure is reduced and the shell free of the gases. By thus freeing the shell of the gases, and by the construction herein, little or no damage is done to the shell by the explosion or the resultant gases and products of combustion, thus enhancing the life of the casing or shell and its appurtenances, it being only necessary to recharge the fuse with a new fuse strip or element.

When the fuse has been disrupted or blown out, and it is desired to renew or refill it, the operator simply removes the end caps by turning them with his thumb and fingers, without the use of tools or other appliances, and without the necessity of removing screws or other fastening devices, and then removing the washers and the damaged fuse strip, and the fuse is then ready for reassembling or refilling with a new fuse element or strip, as in the assembling of the device as hereinbefore described, and without any considerable trouble or delay, so that the line in which the fuse was employed will not be kept out of service any considerable length of time.

We wish to be understood as not limiting the invention to the exact details of construction herein shown and described, as the same may be changed in various ways, and still be within the scope of the appended claims.

45. What we claim is:

1. An electric fuse, comprising a tubular body portion, metallic externally screw-threaded open-ended ferrules fitted on the ends of said body portion and having their outer ends projecting beyond the ends of the body portion to form seats thereon within the ferrules, independent washers adapted to be fitted in the ends of said ferrules and engaging said seats and adapted to removably anchor a fuse element in said body portion, and internally screwthreaded end caps adapted to be screwed upon said ferrules and engage the ends of the fuse strip to hold them in contact with the anchoring washers and to hold said washers in place.

2. An electric fuse, comprising a casing having circumferential grooves near its ends, means for supporting a fuse element in said casing engaging the ends thereof, and end caps fitted upon the ends of the casing and

inclosing said grooves, said grooves affording a gas chamber within the end caps.

3. An electric fuse, comprising a casing having external screwthreads near its ends, and circumferential grooves in said casing between said screwthreads and the ends of the casing, means for supporting a fuse element within the casing engaging the ends of the casing, and internally screwthreaded caps adapted to be screwed upon the ends of the casing to hold the fuse element supporting means in place, the said grooves affording gas chambers within said end caps.

4. An electric fuse, comprising a casing, metallic externally screwthreaded ferrules fitted upon the ends of said casing and having a circumferential groove formed therein, means for supporting a fuse element in said casing, and internally screwthreaded caps adapted to be screwed upon the ferrules to hold the fuse element supporting means in place, the said groove affording a gas chamber within the end caps.

5. An electric fuse, comprising a casing of insulating material, metallic ferrules, having external screwthreads on their inner ends, fitted on the ends of said casing, and having a circumferential groove formed therein between said threads and their outer ends, means for supporting a fuse element in said casing engaging the ends of the casing, and internally screwthreaded caps adapted to be screwed upon said ferrules to hold the fuse element supporting means in place, the grooves in said ferrules affording gas chambers within the end caps.

6. An electric fuse, comprising a casing of insulating material, metallic ferrules having external screwthreads on their inner ends fitted on the ends of the casing and projecting beyond the ends of the casing at their outer ends to form seats in said ferrules, and circumferential grooves in said ferrules between said threads and the outer ends of the ferrules, washers fitted in the seats in the ends of the casing and within the ferrules and engaging the ends of the casing and adapted to removably support a fuse element in said casing, and internally screwthreaded end caps adapted to be screwed upon said ferrules and engage the ends of the fuse element to hold them in contact with said washers, the grooves in said ferrules affording gas chambers within said end caps.

7. An electric fuse, comprising a casing of insulating material having reduced portions at its ends, metallic ferrules having external screwthreads on their inner ends fitted on the reduced ends of said casing and projecting beyond the ends of the casing at their outer ends to form seats in said ferrules, and circumferential grooves rolled into said ferrules and casing between the threads and the outer ends of the ferrules, washers

125

130

fitted in the seats in the ends of the ferrules and engaging the ends of said casing and adapted to removably support a fuse element in said casing, and internally screwthreaded 5 end caps adapted to be screwed upon said ferrules and engage the ends of the fuse element to hold them in contact with the washers, the grooves in said ferrules affording gas chambers within the end caps.

10 8. An electric fuse, comprising a casing having screwthreads at its ends, washers fitted in the ends of the casing, a fuse strip arranged in said casing and having its ends projecting beyond said washers and bent 15 down upon the outer face of said washers,

screwthreaded end caps adapted to fit upon the screwthreaded ends of the casing and engage the ends of the fuse element to hold said washers in place, and a set screw fitted in the head of said end caps and adapted to be forced against the bent ends of the fuse element and exert outward pressure on the end caps, as and for the purpose described. 20

In testimony whereof, we have hereunto set our hands, this 15th day of June, 1918. 25

FRANK C. LA MAR.
PETER J. HOPKINS.
